UNITED STATES PATENT OFFICE.

JULIUS W. McAfee, of New York, N. Y., assignor, by mesne assignments, to
RELIANCE DRYING ROOM COMPANY, of Chicago, Illinois, a corporation of
Illinois.

DRYING-ROOM.

1,181,398

Specification of Letters Patent.

Patented May 2, 1916.

Application filed June 23, 1915. Serial No. 35,773.

To all whom it may concern:

Be it known that I, JULIUS W. McAfee, a citizen of the United States, residing at New York, in the county of New York and State of New York, have invented certain new and useful Improvements in Drying-Rooms, of which the following is a specification.

The present invention relates to improvements in drying rooms, especially adapted for use in drying fillers, stains, varnishes, enamels, and kindred liquid products.

The object of the invention is to provide mechanical means which simultaneously act to draw the air through the heating chamber, and project it into the drying chamber, and also to humidify the air at its entry into the drying chamber, and to draw fresh air into the heating chamber.

Further objects of the invention are to provide deflecting means for causing the air to circulate to all portions of the drying chamber; and to provide means for inducting and educting proportionate amounts of air from the room, and to provide means for controlling the amount of eduction.

The invention further consists in the features of construction and combination of parts hereinafter described and claimed.

In the drawings: Figure 1 is a vertical section of the drying room of the present invention; Fig. 2 is a sectional plan view of said room; Fig. 3 is a section on line 3-3 of Fig. 1, looking in the direction of the arrow; Fig. 4 is a section on line 4-4 of Fig. 1, looking in the direction of the arrows. Fig. 5 is a front elevation of a suitable form of combined fan and humidifying apparatus adapted for use with the present invention; and Fig. 6 is a sectional elevation of the same.

In the art to which the present invention relates, it is necessary to cause a constant circulation of air through the room in which is located the work to be treated.

In the present invention, mechanical means in the form of a fan are provided for drawing the air from the heating chamber and delivering it to a point centrally of the room. This same means injects a certain amount of humidity into the air. The air upon entering the drying chamber is deflected by baffles, to produce a circulation throughout the room; and the fan acts to blow the air toward said baffles.

Referring now to the drawings, the room comprises a top wall 5, a bottom wall 6, side walls 7, and end walls 8. In the construction shown, all of these walls, except the bottom wall, are of double construction, producing an air chamber therearound. This feature, however, is optional with the builder.

Located adjacent one or more of the side walls of said room, is a chamber 9 formed by a screen 10, a top wall 11, a portion of the bottom wall 6, and a portion of the side wall 7 with which the screen is associated. In this chamber is located a heating element 12 of any suitable nature, and an opening 13 is formed approximately at the center of the top wall 11 of said chamber. Adjacent this opening is placed a combined mechanical fan and humidifying apparatus 14, as, for instance, a machine of the nature of that which is now upon the market and termed "Hygroso," the details of which are shown in Figs. 5 and 6, although, of course, any other suitable means may be employed, it being understood that the details of the humidifying apparatus shown are not to be considered as a part of the present invention. Located at the bottom of the wall 10, and preferably at the extreme ends thereof, are openings 15 for permitting a passage of air from the drying chamber into the heating chamber 9, and the passage of a portion of the recirculated air out through the eduction passage.

Air induction flues 16 are located at the lower portion of the chamber 9 and, as shown, are positioned centrally of said chamber. These induction flues are in the form, as shown, of an L-shaped duct, communicating at one end with the interior of the heating chamber, and at the other end with the outside of the drying room. In order to effectively distribute the air passing out from the heating chamber, I provide a ceiling deflector 17 and a side wall deflector 18. Owing to the fact that, in certain instances, it may not be desirable to educt as much of the air from the drying room as in other instances, I provide a sliding door 19 for controlling the size of the discharge opening of the eduction flue. When the air passes through the openings 15, it enters an eduction opening 19 located above the heating element, and passes out through an eduction flue 20, the size of the discharge open-

ing of which is controlled by the door 18, and a suitable deflector 21 being provided to facilitate the entrance into the eduction flue. It will be noted that the air before entering the eduction flue passes over the heating means 12, whereby its speed of upward movement is accelerated.

The combined fan and humidifying apparatus shown in the drawings, by way of illustration, is constructed as follows: The apparatus is carried by a bracket 23 which supports an electric motor 24, the shaft of which at one end carries a fan 25 partially screened at the rear by a shield 26 so arranged as to deflect currents of air generated by the fan to the front. The forward end of the motor shaft carries a dish-shaped disk 27 which is partially housed by a circular casing 28 which is open to the front, and immediately adjacent to the periphery of the disk 27 is a ring shaped grid 29 having formed thereon a large number of fine teeth all projecting forward and terminating in very close proximity to the periphery of the disk. Water is supplied through a small tube 30 which extends obliquely downward and outward and terminates at a point inside of the dish-shaped disk and near the center thereof. The supply of water may be regulated by means of a thermostatically controlled regulator 31 or in any other suitable manner.

The motor serves to simultaneously rotate the fan and the disk at a very high rate of speed, with the result that water, in measured quantity, which is delivered to the center of the disk, will be rapidly and violently thrown by centrifugal action against the surrounding teeth of the grid which serves to break up the drops of water into a very fine mist which will be carried out of the room by the currents of air created by the fan. Obviously, the device can be used solely for fanning purposes, in cases where the air is already sufficiently humidified. Any surplus water which may overflow from the apparatus will be caught and drained off through a drain pipe 32.

The circulating action of the air is as follows: Fresh air enters through the flues 15 and is delivered into the heating chamber 9 below the heating elements 12. It then passes through said heating element, and in doing so is heated and caused to rise upwardly. The draft action of the fan and humidifier 13 draws said heated air to the opening 13^a, from whence it is blown outwardly into the drying chamber 22, and in passing outwardly humidity is added thereto. The air flows across the upper portion of the room and strikes the ceiling deflector 16 and is deflected downwardly; then by the action of the side wall deflector 17, it passes toward the end walls 8 of the room, thus causing a circulation throughout the room.

The air passes through the openings 14 and re-enters the heating chamber. A certain portion of the recirculated air is deflected by the member 21, and passes out through the eduction flue 20, the remaining portion being again drawn through the heating chamber by the action of the fan, and projected into the drying chamber.

From the foregoing, it will be apparent that there is a continuous and complete circulation of air through the drying chamber at all times. The air is drawn through the heating chamber and projected into the drying chamber in a manner to produce a circulation to all parts thereof, and that the same device which draws the air through the heating chamber blows it outwardly into the drying chamber.

I claim:

1. In a drying room, the combination of a heating chamber and a drying chamber, and a combined mechanical fan and humidifying means located adjacent the upper portion of the heating chamber, substantially as described.

2. In a drying room, the combination of a heating chamber and a drying chamber, an opening at the upper portion of the heating chamber, and a combined mechanical fan and humidifying apparatus adjacent said opening, substantially as described.

3. In a drying room, the combination of a heating chamber and a drying chamber, means for admitting fresh air to the heating chamber at a point below the heating means, a combined mechanical fan and humidifying apparatus above the heating means, and means for educting air from the drying chamber, substantially as described.

4. In a drying room, the combination of a heating chamber and a drying chamber, a combined mechanical fan and humidifying apparatus at the upper portion of the heating chamber, a deflector at the ceiling of said room for deflecting the air downwardly, and deflecting means on the opposite side of said room from the heating means for deflecting the air along the wall of said room with which said side wall deflector is associated, substantially as described.

5. In a drying room, the combination of a heating chamber and a drying chamber, means for admitting fresh air to the heating chamber, a combined fan and humidifying apparatus adjacent the upper end of the heating chamber, an eduction passage at the end of the heating chamber communicating at its lower end with the interior of the drying chamber, and heating means within the eduction chamber for accelerating the upward flow of air therethrough, substantially as described.

6. In a drying room, the combination of a heating chamber and a drying chamber, means for admitting air to the heating

chamber, a combined fan and humidifying apparatus at the upper part of the heating chamber, an eduction opening, and means for regulating the size of the eduction opening, 5 substantially as described.

7. In a drying room, the combination of a heating chamber and a drying chamber, means for admitting fresh air to the heating

chamber, means for blowing said air into the drying chamber, and deflectors for distributing said blown air about the drying chamber, substantially as described. 10
